Assistant Examiner — Sanjeev Paul

CLAIM

(57) The ornamental design for a neck and chin support pillow, as shown and described.

DESCRIPTION

FIG. 1 is a front view of a pillow showing my new design;
FIG. 2 is a back view thereof;
FIG. 3 is a side view thereof;
FIG. 4 is a top view thereof;
FIG. 5 is a bottom view thereof;
FIG. 6 is a front perspective thereof;
FIG. 7 is a back perspective view thereof; and,
FIG. 8 is a view in use.

The broken lines shown in the drawings are included for the purpose of illustrating environmental structure and form no part of the claimed design.
